Philip Sawyer, Lee Kennedy

UNITED STATES PATENT OFFICE.

MILO O. HART, OF EUCLID, OHIO, ASSIGNOR TO THE POMPEIAN COMPANY, OF CLEVELAND, OHIO, A CORPORATION OF OHIO.

VANITY CASE.

Application filed June 9, 1923. Serial No. 644,302.

To all whom it may concern:

Be it known that I, MILO O. HART, a citizen of the United States, residing at Euclid Village, county of Cuyahoga and State of Ohio, have invented certain new and useful Improvements in Vanity Cases, fully described and represented in the following specification and the accompanying drawings, forming a part of the same.

10 This invention relates to certain improvements in the small boxes for holding cosmetics, as powder and rouge, in compact form and commonly known in the art as vanity boxes.

15 These vanity boxes for commercial saleable purposes must be of attractive appearance and of such size that they may be readily carried in the small handbag or pocketbook. They must, furthermore, be of such character that the powder and rouge is easy of access for use and in which powder and rouge may be replaced or refilled in the boxes after depletion and retained in position therein after such refilling or replacement.

20 These boxes, furthermore, should be provided with a reflecting surface, as a mirror.

25 It is the especial object of the present invention to provide a vanity box for holding rouge and powder in the form of compacts which should be of attractive appearance and which shall be constructed so that powder and rouge compacts may be easily and quickly refilled or replaced in the box and when so placed in the box held securely in position.

30 A further object of the invention is to provide a vanity box having a reflecting surface, such as a mirror, and improved means for holding the mirror in position.

35 With these and other objects not specifically referred to, the invention consists in certain novel parts, arrangements and combinations which will be more particularly described in connection with the accompanying drawings and the novel features thereof pointed out in the claims hereunto annexed.

In the drawings—

Figure 1 is a face view of the improved box shown with the cover open;

Figure 2 is a side view of the box shown in Fig. 1, the parts being closed;

Figure 3 is a front view of Fig. 2;

Figure 4 is a sectional view on an enlarged scale taken through the center of the box, the box being shown as closed;

Figure 5 is a detail sectional view on an enlarged scale of parts of the box shown in Fig. 1;

Figure 6 is a detail sectional view partly broken away of the holder plate; and,

Figure 7 is a detail sectional view partly broken away of the means for securing the holder in position in the box, the section being taken on line 7—7 of Fig. 5.

Referring now to these drawings in detail—the box is preferably made of light metal and includes a bottom compartment 1 and a cover 2, these parts being pivotally associated on a barrel hinge 3. To provide a box of attractive appearance the cover and bottom members are preferably shaped as shown, that is, the box is substantially rectangular in shape, having flat portions 4, 5, and ends and sides 6, 7, tapering or beveled toward each other, as best shown in Figs. 2 and 3. The box shown is particularly intended for holding powder and rouge in compact form. These powder and rouge compacts are produced by compacting the powdered cosmetic with a suitable binder on a plate or disk of some thin white material, these compacts being thus made by the manufacturer and replaced or refilled in the box by the user as required.

Provision is made by the present invention to securely hold these compacts in the box, these holding means being such as to permit the ready withdrawal and replacing of the compacts and their associated plates.

In the particular construction illustrated there is provided what may be termed a holder plate 8 which is provided with an aperture 9 for the powder compact and an aperture 10 for rouge, the powder aperture being of greater dimensions than the rouge aperture. This holder plate is or may be formed from a sheet of metal and the apertures 9, 10, are surrounded by walls 11, 12, these walls being formed by turning in the metal of the plate so that the metal projects downwardly, the bottom of these walls extending downwardly and resting on the bottom 1 of the box.

The upper part of the top of the plate is flat and if desired may be formed with a partition 13 extending

across the top between the rouge and powder compartments.

The top of the holder plate is turned downwardly to form a flange 14 which has 5 a snug fit within a peripheral flange 15 on the bottom of the box. To securely position this holder plate in the box securing means may be provided, such as projections 16 (see Fig. 7) which may snap under a 10 shoulder 17 formed on the flange 15 before referred to, this plate being thus securely held in position in the box.

Cooperating with the walled apertures of the holder plate are locking rings 18, 19, 15 formed preferably of a resilient spring metal, open at each end and having a frictional engagement with the walls 11, 12, before referred to. The lower end of these rings is slightly inturned, as indicated, at 20, and the upper end is formed with a flange 21 adapted to fit over the edge of the holder plate surrounding the apertures and provide an attractive appearance. If desired, the holder rings may have one or 25 more slight projections 22 to insure a firm engagement with walls 11 and 12, and to provide ready removal of the holder rings the upper edge of the flange 21 may be provided with a slightly flattened portion 23 30 forming a lip which may be engaged by the fingernail to remove the ring from locking contact with the walls 11 and 12.

With this construction the inturned edge 20 of the locking ring fits over the plate 35 or disk of the compact holder and securely positions the compact in the box. In the best constructions an improved plate or disk for the compact will be provided which will more securely hold the powder in place 40 on the disk and which is better adapted to cooperate with the locking ring for positioning in the box. This improved compact holder is in the form of a dish-shaped plate 24, this plate being concaved in cross section 45 having sides 25 rising upwardly and outwardly from the bottom of the plate and, furthermore, the outer edges of this plate are slightly beveled, as indicated at 26. With this construction a sort of pocket is 50 formed on which the powder is readily compacted and which acts to hold the powder against chipping off. Furthermore, with this construction the plate and holding ring cooperate to permit convenient removal and 55 replacement in the box. It is to be understood that while this dish-shaped plate is the preferred form, plates of other shapes, as for instance a flat plate, may be used if desired.

60 Boxes constructed in accordance with the invention will include a mirror or similar reflecting surface and, in the particular box shown, this reflecting surface is in the form of a glass mirror 27 positioned in the cover 65 of the box. Improved means are provided

by the present invention for securing this mirror in the cover. In the particular construction illustrated there is provided a mirror holder in the form of a plate 28 soldered or otherwise suitably secured to 70 the inside of the cover 1 before referred to. This plate is provided with an upwardly extending flange (assuming the cover to be open) 29 which forms a pocket for the mirror 27. Cooperating with this flange 75 is a locking plate having a central aperture for the mirror and an upturned flange 31, this flange 31 fitting, as by friction fit, on the outside of the flange 29 before referred to. With this construction the mirror is 80 firmly held in place but, in case of injury thereto, may be readily removed and another mirror inserted in its place.

In the best constructions means are provided for securing the cover to the bottom 85 which, in the present instance, is a spring catch indicated generally by the numeral 32 in Fig. 3, this catch securing the flange 33 of the cover to the flange 15 of the bottom 90 before referred to.

While the invention has been shown and described in its preferred form it will be understood that certain changes and variations may be made to the structure shown and described without departing from the 95 invention as defined in the claims hereunto annexed.

What I claim is.

1. In a vanity box, a compact holding compartment, a cover pivotally associated therewith by a hinge, a plate having vertical flanges secured inside the cover and spaced from the sides of the cover and the hinge, a mirror positioned within the flanges, and a plate having vertical flanges extending 100 reversely to those of the first plate and in frictional engagement therewith, said second plate also having horizontal flanges engaging the mirror near its edges.

2. In a vanity box, a compact holding body, a cover pivotally associated therewith by a hinge, said cover having side portions sloping downwardly from a flat central portion, a plate having a rectangular flange located inside the cover in the flat portion thereof and spaced from the sloping sides, said flanges forming a pocket, a mirror in the pocket, and a removable securing plate having a rectangular flange in frictional engagement with the flange of the 110 first named plate, and a horizontal flange 115 engaging the mirror near its edges.

3. In a box for holding cosmetics, a bottom compartment, a flanged plate secured in the compartment and provided with a walled aperture, a compact having retaining plates formed with upwardly bevelled edges, a locking ring frictionally engaging with the walls of the aperture, the lower end of said ring being inturned to engage 120

the locking plate and the upper end having a projection extending above the plate by which the ring may be removed, and a cover.

4. In a vanity box, having a bottom and a cover, a flanged plate secured in the under side of the cover, a reflecting surface positioned in the plate, a locking member for holding the mirror in position comprising

a plate having a flange against which the mirror may bear, and a holding flange 10 frictionally engaging with the flange of the first named plate.

In testimony whereof, I have hereunto set my hand.

MILO O. HART.
